RAILWAY SIGNALING SYSTEMS

Wesley Y. Speight, Bellaire, Tex., assignor to Westinghouse Air Brake Company, Wilmerding, Pa., a corporation of Pennsylvania

Filed Oct. 28, 1957, Ser. No. 692,927

8 Claims. (Cl. 246—34)

My invention relates to a railway signaling system. More particularly, my invention relates to a coded track signaling system using master and feedback codes to control the wayside signals governing train movements in opposite directions through a stretch of single track railway.

Coded track signaling systems using master and feedback codes, also termed normal and reverse codes, respectively, are well known in railway signaling art. They have been used frequently for signaling systems for single track railways of the form known as Absolute Permissive Block signaling (hereinafter designated A.P.B.) and have also been used to provide additional controls through the reverse code for such functions as approach lighting of signals, additional block indications, and switch control. Considering herein only those coded track systems using a frequency code for the master or normal coded track current, such systems use a plurality of code rates to provide a plurality of indications in the direction governed by the master code. The reverse code heretofore has generally been limited to a polar code with two active indications, that is, two types of code pulses, and one indication obtained through the no-code condition. Even though the normal code may have a plurality of rates, this limitation for the reverse code still exists since such reverse codes must be independent of the normal codes as to the indications which they carry. That is, although the reverse code is generated as a result of the reception of the normal code through the track rails, the indication transmitted by the reverse code at any particular time must be independent of the indication being transmitted at the same time by the normal code in accordance with the code rate used. It is understood, of course, that the code rate of the reverse code is always identical with that of its master driving code.

The provision of additional indications carried by the reverse code is an advantage in A.P.B. signal systems and also in systems for approach lighting and other functions. In A.P.B. signaling, additional indications carried by the reverse code provide for overlap of signal controls at the station locations. Heretofore, it has been frequently necessary to reverse the direction of flow of the normal and reverse codes from one track section to another in the single track stretch in order to obtain the desired overlap throughout the station areas for additional safety in the system. With an additional indication possible in the reverse code, it will not be necessary to reverse the code direction from one track section to another. In other words, the reverse code may carry the overlap controls for the traffic direction in which it governs in a manner similar to the carrying of such controls by the normal code. With an additional indication available in the reverse code direction, the approach lighting of signals section by section is possible in such A.P.B. systems rather than from station to station. However, it is apparent to those skilled in the art that additional indications in the reverse code

2

are possible only through combinations of the two available polarities. In other words, each additional indication comes only by providing an active indication comprising some combination of positive and negative polarity pulses.

Accordingly, an object of my invention is to provide a coded track signaling system using normal and reverse codes and having an additional indication in the reverse code direction.

10 A further object of my invention is to provide a coded track signaling system having at least three indications in both the master and feedback code directions.

Another object of my invention is to provide an A.P.B. signaling system using normal and reverse track codes with each type code having sufficient active indications to carry all the required controls for governing traffic movement in one direction of travel.

15 It is also an object of my invention to provide, in a coded track signaling system, a reverse code generator capable of supplying three independent, active indications.

20 Still another object of my invention is to provide a reverse code generator for coded track signaling systems which is capable of transmitting a polarized reverse code at times having a combination of the available polarities of track current.

25 Other objects and features of my invention will become apparent from the following specification when taken in connection with the accompanying drawings.

30 In signal systems embodying my invention, there is provided, for each track section, a master or normal coded track circuit carrying three frequencies or code rates for control of the wayside signals. This master code is transmitted from the same end of each track section and

35 controls the signal governing train movements entering at the opposite end of the section. These normal code pulses are received at the other end of the section by a track relay which drives the decoding circuit arrangement and the reverse code generator. The reverse code generator includes, in a first form of the apparatus, a double armature relay as the reverse code transmitter relay and a pair of stepping relays to at times selectively pole change the connections to the transmitter relay. In a second form of the apparatus, two reverse

40 code transmitter relays are selected by a pole changing relay, the entire arrangement being driven by the track relay responsive to the normal code pulses. In either form, the operation of the reverse code generator means results in the transmission of reverse code pulses at times having a single polarity and at other times having alternately opposite polarities, that is, positive and negative pulses. These reverse code pulses are transmitted in the usual manner, one during each off-period of the normal code.

50 55 The normal frequency code is decoded by a mechanically tuned circuit arrangement. The two higher code speeds control the clear and approach indications of the associated signal governing entrance of trains into the section. The lowest code speed is used only as a carrier for the reverse code, the signal governing movements in the normal code direction being controlled to its stop indication during this period. The polar reverse code is decoded at the opposite end of the section, that is, the end from which the normal code originates, using relay type decoding. The relay circuit arrangement includes a decoding relay for each polarity and a third relay to detect any code following operation of the track relay.

60 65 The decoding of a combination of polarities received by the track relay results in the display of a clear indication by the associated entering signal. Pulses of a single polarity, which may be selected as the positive polarity, result in an approach indication while pulses of

the other polarity alone result in a stop indication and are used to control overlap or approach lighting.

Referring now to the drawings, Fig. 1 shows, diagrammatically, apparatus embodying a first form of my invention in a signal system for a single section of single track between two signal locations.

Fig. 2 shows, diagrammatically, apparatus embodying a second form of my invention at the reverse code transmitting end of the track section. The apparatus of Fig. 2 cooperates with the apparatus at the other end of the section shown in Fig. 1.

In each of the drawings, similar reference characters refer to similar parts of the apparatus.

In the drawings, conventional symbols commonly used in the art have been used wherever possible in order to simplify the showings for an easier understanding. For example, slow-acting relays are so designated by vertical arrows drawn through the movable portion of the relay contacts, the arrow pointing up or down to indicate the direction in which the relay is slow acting. Biased relays are designated by arrows shown within the winding symbol for that relay. Such relays are characterized by the operation of relay armatures to close front contacts only when the energizing current flows through the relay winding in the direction of the arrow. Flow of current in the opposite direction, as well as deenergization of the relay winding, results in the release of the relay armature closing back contacts. Magnetic stick relays are also designated by an arrow shown within the symbol for the relay winding, but these relays are distinguished from the biased type by also showing the movable portion of the relay contacts in the vertical position. When current flows through the relay winding (either winding in two winding relays) is in the direction of the arrow, these contacts are operated to the left-hand or normal position. Flow of current through either or both windings of such relays in a direction opposite to the arrow results in the closing of right-hand or reverse contacts. These relays have a further characteristic of holding the contacts in the position to which they were last operated when the relay winding or windings are deenergized. A further conventional symbol is the showing of contacts of code following relays in a dotted manner in both the energized and released positions. Such showing indicates that the movable portion of the contact is continuously following a coded current, at least in the condition shown in the drawings, so that it alternately closes front and back contacts. Where such a code following contact normally occupies one or the other position and only at times follows code, the normally occupied position is shown by a solid line with the code following position indicated by the aforementioned dotted line.

The rails of the track section are shown by the conventional single line symbol commonly used. The track circuit connections to the rails must thus also be shown conventionally by a dotted line and bracket joining the two leads from the track circuit arrangement at each location. To assist in the understanding of the circuits traced, (+) and (-) symbols are shown adjacent the leads at each end of the track section to indicate those track leads which are connected to the same rail. The wayside signals in the track diagram are shown by conventional semaphore symbols with a heavy line indicating the position which the signal usually occupies, herein the vertical or clear position. It is to be understood, of course, that the actual wayside signals may be of any type well known in the art, for example, color light, search light, or position light signals. Such showing as is necessary in the circuit arrangement of the drawings is in the form of color light signals having three lamps, green, yellow, and red, respectively designated G, Y, and R. Each set of lamps shown is connected to the corresponding trackside symbol by a dotted line. Finally, each location is provided with a local source of direct current energy which may be a battery of proper size and capaci-

ty. However, for simplicity, the source of energy as such is not shown and only its positive and negative terminals are indicated by the usual reference characters B and N, respectively.

Referring now to Fig. 1, there is shown across the top of this drawing a conventional track diagram of a single track section which extends between a double signal location at the left or west end and a similar double signal location at the right or east end. The section, designated 5 2-3T, is set off from the remainder of the stretch by insulated joints, shown conventionally by heavy bars drawn perpendicular to the single line track symbol. As previously indicated, this one section may be considered as part of a single track stretch between stations which is provided with a A.P.B. signaling system. At the west end of section 2-3T, signals 1G and 2G, respectively, govern traffic out-of and into the section. At the east end, signals 3G and 4G, respectively, govern traffic into and out-of the same section. Stated in other words, signals 1G and 3G govern westbound train movements into and out-of section 2-3T, while signals 2G and 4G govern eastbound train movements into and out-of the section. As will appear hereinafter, the apparatus shown controls directly only signals 2G and 3G, the opposing entering signals for this track section.

Section 2-3T is provided with two coded track circuits, one for each direction of traffic movement. Each track circuit controls the entering signal at the end of the section at which the code pulses are received. Each track 10 circuit is supplied with energy from a track battery generally designated by the reference character TB, with a prefix corresponding to the entering signal at that location. Each section is further provided with a track relay generally designated by the reference character TR again 15 plus a prefix corresponding to the entering signal at that location. Thus, at the west end, there is located track battery 2TB and track relay 2TR and at the east end track battery 3TB and track relay 3TR. The master or normal coded track circuit may be traced from the positive terminal of battery 2TB over normal contact *a* of code transmitter repeater relay 2CTR, one rail of the track section, back contact *an* of reverse code transmitter relay 3RC, the winding of relay 3TR in the direction of the arrow, back contact *ar* of relay 3RC, and the other 20 rail of the track section to the negative terminal of battery 2TB.

Relay 3RC is a biased relay having two separate and distinct armature structures, termed the normal and the reverse armatures, each of which is provided with an associated set of contacts whose operation is separate from that of the other set of contacts. Each armature is responsive to current flowing through the single relay winding in one direction only, operating to close associated front contacts only under this condition. At all other 25 times, the armatures are biased to close associated back contacts, as in any biased relay. The normal armature of relay 3RC is responsive to current flowing through the winding in the direction of the left-hand arrow, designated *n*, within the relay winding symbol. The reverse armature is responsive to current flow in the opposite direction as indicated by the second arrow designated *r*. The contacts associated with the normal armature are designated by a suffix *n* added to the conventional letter reference for the contact, while the contacts associated with the reverse armature are identified by the suffix *r* added to the otherwise conventional letter reference for the contact. As these contacts are referred to hereinafter, the use of these suffixes will serve to distinguish between the two sets of contacts. Track relay 2TR located at the west end of the section is a similar type relay and its contacts associated with the left and right armatures are likewise distinguished by the use of similar suffixes added to the conventional letter reference characters for the contacts. It is to be understood that either 30 35 of these double armature biased relays may be replaced

by two ordinary biased relays, each having a single armature. If used, the windings of the two relays are connected in series so poled that one relay is responsive to current flowing in one direction through the series circuit while the second relay is responsive to current flowing in the opposite direction.

The reverse code track circuit may be traced from the positive terminal of track battery 3TB over front contact *an* of relay 3RC, one rail of the track circuit, reverse contact *a* of relay 2CTP, the winding of relay 2TR, the other rail of the track section, and front contact *bn* of relay 3RC to the negative terminal of battery 3TB. In the circuit just traced, it is evident that the positive terminal of the track battery is connected to the rails through the lead designated by the symbol (+). At the other times in the operation of the reverse code circuit, front contacts *ar* and *br* of relay 3RC replace, respectively, front contacts *an* and *bn*. It is obvious from an inspection of the drawings that, in this condition, the positive terminal of the track battery is connected to the rails over the track lead designated by the symbol (-), so that the polarity of the reverse code pulses is pole changed when the connections are made in this second manner.

The apparatus shown in Fig. 1 at the west end of the track section is not actually a part of my invention, but necessary for cooperation with the circuits of my invention in order to provide a complete signaling system of the A.P.B. type. The circuit arrangement at the west end of the section is disclosed in the copending application for Letters Patent of the United States, Serial No. 692,926, filed on the same date as this application by C. W. Failor and C. E. Staples for a Railway Signaling System, the two applications having the same assignee. I shall describe briefly the operation of the circuits at the west end and, in more detail, the cooperation between these circuits and the circuits at the east end embodying my invention. Reference is made to the copending Failor and Staples application for a disclosure of a complete A.P.B. signaling system in which the circuits of my invention may be used.

As part of the apparatus at the west end of the section, three code transmitters are provided which serve to establish code rates for the master track code. Each of these transmitters is designated by the reference character CT with a numerical prefix which indicates the code rate in code pulses per minute at which the corresponding transmitter operates. For example, code transmitter 180CT operates at the code rate of 180 pulses per minute so that it alternately closes its front and back contacts at this code frequency. Any well known type of code transmitter may be used, but for purposes of this description they are shown and will be considered as being of the relay type which is particularly well known in the art. Each of the code transmitters is permanently energized, their windings being connected directly between terminals B and N of the local source. Thus, each transmitter alternately closes its front and back contacts at the code rate designated by the numerical prefix associated with that transmitter.

The actual transmission of the master code pulses into the rails of the track section is controlled by the code transmitter repeater relay 2CTP. Relay 2CTP is of the magnetic stick type so that its contacts will remain in the normal or reverse position to which they were last operated if the relay winding is deenergized. One circuit for energizing relay 2CTP may be traced from terminal B over normal contact *b* and the winding of relay 2CTP, front contact *a* of signal repeater relay 1GYP, and back contact *a* of transmitter 180CT to terminal N. It is obvious that the flow of current in this circuit through the relay winding is such as to cause relay 2CTP to operate its contacts to the reverse position, closing reverse contact *b*. Back contact *a* of transmitter 180CT is

periodically opened, and during this period, the corresponding front contact *a* is closed. A circuit is then established from terminal B over back contacts *an* and *ar*, in series, of relay 2TR, front contact *a* of transmitter 180CT, front contact *a* of relay 1GYP, and the winding and reverse contact *b* of relay 2CTP to terminal N. The flow of current in this circuit is such as to cause the relay to operate its contacts to the left-hand position, closing normal contact *b*. Back contacts *an* and *ar* of relay 2TR assure that a normal code pulse will not be transmitted if the track relay is held energized by foreign current or if the reverse code pulse is unnecessarily prolonged. It is obvious, therefore, that, as contact *a* of transmitter 180CT alternately closes in its front and back positions, relay 2CTP is alternately energized to operate its contacts to their normal and reverse positions, respectively, so that the relay follows the code rate of the code transmitter.

At times the circuit for relay 2CTP is completed over back contact *a* of relay 1GYP, back contact *b* of directional stick relay 1S, and front and back contacts *a* of code transmitter 75CT. Under these conditions, the operation of relay 2CTP is at the 75 code rate. If back contact *a* of relay 1GYP and front contact *b* of relay 1S are closed in series, the circuits for relay 2CTP are controlled by contact *a* of transmitter 120CT so that the transmitter repeater operates at the 120 code rate. It is obvious from the previously traced track circuits that the operation of contact *a* of relay 2CTP alternately connects track battery 2TB and track relay 2TR to the rails of the track section, these connections being alternated at the code rate at which the transmitter repeater relay is controlled.

As indicated by the note on the drawing, signal repeater relay 1GYP is energized if signal 1G displays a green or yellow aspect to provide a proceed indication for westbound trains. It is to be understood that an indication of the signal position may also be obtained from the position of the home and distant control relays for the signal. For purposes of simplicity, however, the circuit is shown using only signal repeater relay 1GYP to repeat the signal position, the other arrangements being well known in the art. Directional stick relay 1S, as indicated in the drawing, is associated also with signal 1G in order to provide for following moves in the same direction through the track section. Relay 1S may be controlled in various ways well known in the art, with a specific example of the advance or two-track-circuit pickup arrangement being disclosed in the aforementioned Failor and Staples application. The control of relays 1GYP and 1S is not part of the circuit arrangement embodying my invention and thus these relays have been shown conventionally in order to simplify the drawing and the description.

The reverse code received at the west end of the section by track relay 2TR is decoded by a relay circuit arrangement driven by contacts of the track relay. The distant control relay 2D is energized over an obvious circuit including front contact *br* of relay 2TR and the winding of relay 2D. The relay winding is shunted by a resistor-capacitor combination which provides relay 2D with sufficient slow release characteristics to permit the relay to retain its front contacts closed if contact *br* of relay 2TR is only periodically closed in response to code pulses. A somewhat similar circuit for home relay 2H is traced from terminal B over back contact *br* and front contact *bn* of relay 2TR and the winding of relay 2H to terminal N. Relay 2H is likewise snubbed by a resistor-capacitor combination so that it is provided with a slow release period sufficient to retain its front contacts closed during coding action of contact *bn*. As will appear hereinafter, these snubs must provide a sufficient slow release period that the relays will hold front contacts closed even though they are provided with a pulse of energy only during alternate off-periods of the master code.

The circuit for track repeater relay 2TP includes back contacts *br* and *bn* of relay 2TR, front contacts *a*, in multiple, of relays 2D and 2H, back contact *a* of relay 1S, and the winding of relay 2TP. When front contact *a* of either of the other two decoding relays is closed, the winding of relay 2TP is shunted by a half-wave rectifier, the snubbing circuit further including back contact *a* of relay 1S. When either or both of contacts *br* and *bn* of relay 2TR are following code, relay 2TP is periodically energized and picks up to retain its front contacts closed. However, the relay releases shortly after the interruption of its circuit at front contact *a* of either of the other decoding relays, the snubbing circuit also being interrupted under these conditions. Back contact *a* of relay 1S is included in the circuit for relay 2TP to assure that signal 2G displays a red aspect behind a westbound train occupying the adjacent section to the west.

The aspect displayed by signal 2G is controlled by the position of the decoding relays. Signal 2G is shown, for simplicity, as a color-light signal, although it has been previously mentioned that other types of signals may also be used. The circuit for energizing the green lamp G of signal 2G is traced from terminal B over front contact *a* of relay 2TP, front contacts *b*, in series, of relays 2H and 2D, and lamp G to terminal N. Thus, all of the decoding relays must be energized and picked up in order for the signal to display a green aspect denoting a clear indication. The yellow lamp is energized over a circuit including front contacts *a* and *b* of relays 2TP and 2H, respectively, and back contact *b* of relay 2D. The circuit for the red lamp, which results in a stop indication, may be traced over back contact *a* of relay 2TP or over front contact *a* of relay 2TP and back contact *b* of relay 2H. This second circuit for lamp R assures a display of the stop indication in the event that relays 2D and 2TP are energized due to the operation of only the right armature of relay 2TR.

At the east end, the master code received by track relay 3TR is decoded by an arrangement which includes track repeater relays 180TP and 120TP, distant relay 3D, home relay 3H, and code detection relay 3CD. The circuit arrangement is similar to that shown in the previously mentioned Failor and Staples application. Track repeater relays 180TP and 120TP are each provided with at least one mechanically tuned contact arrangement, this contact being tuned to a code rate corresponding to the numerical portion of the relay reference character. As an example, these relays may be as shown and claimed in Letters Patent of the United States 2,730,592, granted January 10, 1956 to Andrew Hufnagel for a Code Following Relay With Frequency Decoding Contacts. Reference is made to this patent for a complete description of such relays. Briefly, the relay may be provided with one or more code following contacts which repeat any code rate at which the relay is energized. At least one other transfer contact is then mechanically tuned to be responsive only to the selected code rate. For example, contact *a* of relay 180TP is responsive, to alternately close its front and back contacts, only when the winding of relay 180TP is energized by code pulses at the 180 code rate. Contact *a* of relay 120TP is similarly tuned, but is responsive, alternately closing its front and back contacts, only when the relay is energized by pulses at the 120 code rate. The tuned contacts of these relays are so designated by a line drawn through the heel of the movable portion of the contact with a numerical designation denoting the code rate. When the relay winding is energized by pulses of energy at any other code rate, the mechanically tuned contacts remain inoperative with back contacts closed. Contact *b* of relay 120TP is of the non-tuned type and alternately closes its front and back contacts when relay 120TP is energized at any code rate.

Relays 180TP and 120TP are energized over obvious

circuits completed, respectively, at front contacts *a* and *b* of track relay 3TR. Distant relay 3D is then energized by a circuit from terminal B over back contact *a* of directional stick relay 4S, front contact *a* of relay 180TP, and the winding of relay 3D to terminal N. The half-wave rectifier connected in multiple with the relay winding provides a sufficient slow release period for the relay so that its front contacts remain closed as long as the relay winding is periodically energized by the closing of front contact *a* of relay 180TP at the 180 code rate. Back contact *a* of directional stick relay 4S, which is associated with signal 4G and is energized when a train passes signal 4G displaying a clear indication in a manner similar to that previously discussed for relay 1S, assures that signal 3G will display a stop indication behind an eastbound train in the track section adjacent on the east to section 2-3T.

With back contacts *a* of relays 180TP and 120TP closed and also back contact *b* of 120TP, a circuit is completed, including back contact *a* of relay 4S, to charge capacitor C1 from the local source of direct current energy. When front contact *b* of relay 120TP closes during the on-time of the master code, capacitor C1 is discharged over this front contact through the winding of relay 3CD, the circuit being completed from terminal N at the right side of the winding of relay 3CD to terminal N at the left end of resistor R1. Relay 3CD is thus periodically energized at any time that relay 3TR operates at any code rate and is snubbed by a half-wave rectifier to provide sufficient slow-release characteristics to retain its front contact closed during the coding action.

Home relay 3H is also energized if master code at the 180 code rate is received at this end of the track section. Under this condition, the energizing circuit is completed over front contact *b* of relay 3D and front contact *a* of relay 3CD to the winding of relay 3H. At other times, when pulses at the 120 code rate are being received, the circuit for relay 3H includes back contact *a* of relay 4S, back contact *a* of relay 180TP, front contact *a* of relay 120TP, which is responsive only to the 120 code rate, and front contact *a* of relay 3CD. The half-wave rectifier snub is connected in multiple with the winding of relay 3H only when front contact *a* of relay 3CD is closed. Under this condition, relay 3H is provided with a sufficient slow release period to retain its front contacts closed during coding action of contact *a* of relay 120TP. If the coding action of relay 3TR, and thus relay 120TP halts, the release of relay 3CD at the end of its slow release period interrupts the snub circuit and relay 3H releases shortly thereafter.

The control circuits for signal 3G, which is shown as a color-light signal having the lamps G, Y, and R, are similar to those discussed for signal 2G, but do not include contacts of relay 3CD. The circuit for lamp G of signal 3G includes front contacts *a*, in series, of relays 3D and 3H. The yellow lamp Y is energized over back contact *a* of relay 3D and front contact *a* of relay 3H, while an obvious circuit over back contact *a* of relay 3H provides energy for lighting lamp R. Depending on whether signal 3G displays a green, yellow, or red aspect, a clear, approach, or stop indication, respectively, is correspondingly provided.

The reverse code transmitting or generating circuits at the east end of the track section include, in addition to the transmitter relay 3RC previously defined, the front and back contact track repeater relays 3TFP and 3TPB, respectively. Contacts of stick relay 4S and signal repeater relay 4GYP also enter into the operation of the reverse coding circuits. This latter relay repeats the position of signal 4G, being energized if this signal displays a green or yellow aspect. As previously discussed in connection with relay 1GYP, contacts of relay 4GYP could be replaced by various contacts of the distant and

home relays controlling signal 4G, but for simplicity the single repeater has been shown. Relays 3TFP and 3TBP are both of the two-winding, magnetic stick type previously defined. The circuit for the upper winding of relay 3TFP extends from terminal B over front contact c of relay 3TR, reverse contact a of relay 3TBP, and the winding of relay 3TFP to terminal N. A circuit for the lower winding of relay 3TFP includes, in addition to front contact c of relay 3TR, normal contact a of relay 3TBP. Similar circuits for relay 3TBP may be traced over reverse and normal contacts a of relay 3TFP and back contact c of relay 3TR.

Assuming relay 3TBP to be occupying its normal position, it is apparent that if relay 3TR is energized and closes its front contact c, the lower winding of relay 3TFP is energized with current flowing in the direction to operate its contacts to their reverse position closing, specifically, reverse contact a. If relay 3TR is then de-energized, as during the following off-period of the master code pulses, the circuit completed over back contact c of the track relay and reverse contact a of relay 3TFP energizes the lower winding of relay 3TBP with a direction of current flow to cause operation of its contacts to their reverse position, closing reverse contact a. During the following master code pulse, the closing of front contact c of relay 3TR completes a circuit for energizing the upper winding of relay 3TFP, with the direction of current flow being such that the relay operates its contacts to their normal position. During the next off-period of the master code, the upper winding of relay 3TBP is energized over back contact c of the track relay and normal contact a of relay 3TFP. The direction of current flow is such as to cause relay 3TBP to operate its contacts to their normal position, closing normal contact a. The two-relay stepping arrangement has now returned to its initial assumed condition and the closing of front contact c of relay 3TR during the next pulse of master code initiates a repeat cycle of operation. The two track repeater relays thus periodically step between their reverse and normal positions during alternate cycles of the master code. Specifically, relay 3TFP operates, during one on-period of the master code, to close its reverse contacts and, during the next on-period, to close its normal contacts the stepping cycle being completed or assisted by the similar operation of relay 3TBP.

Each time relay 3TR is energized and picks up to close its front contact a, capacitor C2 is charged from terminal B over front contact d of relay 3TR through capacitor C2 and resistor R2 to terminal N. When track relay 3TR releases during an off-period of the master code, and with conditions normal (signals clear) so that relay 4GYP is energized, a first circuit is completed from terminal N through resistor R2, capacitor C2, back contact d of relay 3TR, normal contact b of relay 3TFP, front contact a of relay 4GYP, the winding of relay 3RC, front contact b of relay 4GYP, and normal contact c of relay 3TFP back to terminal N. The charge stored in capacitor C2 discharges through this circuit, the flow of current through the winding of relay 3RC being from left to right so that the left armature is responsive and operates its corresponding contacts. With relay 3TFP in its reverse position, the circuit includes resistor R2, capacitor C2, back contact d of relay 3TR, reverse contact b of relay 3TFP, front contact b of relay 4GYP, the winding of relay 3RC from right to left, front contact a of relay 4GYP, and reverse contact c of relay 3TFP. This time the flow of current discharging from relay C2 is in the direction to cause the right armature of relay 3RC to operate its contacts. It is thus apparent that, with relay 4GYP picked up, the stepping operation of relay 3TFP, as controlled by the code following operation of relay 3TR, causes relay 3RC to alternately operate its left and right hand contacts during off-periods of the master code. From the reverse code track circuits previously discussed, it is apparent that this causes the suc-

cessive pulses of the reverse code to have alternately opposite polarities.

If relay 4GYP is released, one control circuit for relay 3RC may be traced from terminal N through resistor R2, 5 capacitor C2, back contact d of relay 3TR, front contact b of relay 4S, back contact a of relay 4GYP, the winding of relay 3RC from left to right, back contact b of relay 4GYP, and front contact c of relay 4S to terminal N. Since contacts b and c of relay 3TFP are bypassed by this circuit, the pulse of current resulting from each discharge of capacitor C2 is in the direction to cause only the left armature of relay 3RC to operate its contacts. Another circuit arrangement is similar, but includes back contacts b and c of relay 4S instead of the 15 corresponding front contacts. It is apparent that the flow of current through the winding of relay 3RC, under this condition, is reversed so as to be from right to left causing the right armature only to be responsive to operate its contacts. Thus, with relay 4GYP released, but stick 20 relay 4S energized, the reverse code pulses will all be of the positive polarity, while if relay 4S is also released, all of the reverse code pulses will have the negative polarity.

I shall now describe the operation of the signal system 25 for section 2-3T as provided by the circuits embodying my invention. It is believed that, with this operational description, the operation of an A.P.B. signal system for a complete stretch of single track utilizing the circuits of my invention will be obvious to those skilled in the art. 30 In addition, reference is made to the aforementioned Failor and Staples application for further background in the application of these circuits to a complete system.

As shown in Fig. 1, the signal system is in the condition which it assumes when the track stretch is unoccupied, that is, there is no train in section 2-3T or in the 35 stretch of single track between the first station east and west of the illustrated track section. Under this condition, signal 1G displays a clear indication and relay 1GYP is energized and picked up. The operation of relay 40 2CTP is then at the 180 code rate so that the master code pulses flowing in section 2-3T are of this rate. Track relay 3TR follows each code pulse, picking up during the pulse on-time and releasing during the off-period following. Relays 180TP and 120TP repeat exactly the operation of relay 3TR, being energized over its front contacts a and b. Contact a of relay 180TP will alternately close its front and back contacts as it is tuned to the 180 45 code frequency. However, contact a of relay 120TP remains with its back contact closed, as indicated by the solid line position of the movable portion of this contact, since it is tuned to the 120 code frequency and is non-responsive at the 180 code rate. With the track to the east unoccupied, signal 4G is displaying its clear indication so that relay 4S is released. Decoding relays 50 3D, 3CD, and 3H are thus energized and circuits are completed for energizing the green lamp of signal 3G to provide a clear indication on this signal.

With signal 4G indicating clear, relay 4GYP is energized and its front contacts are closed. Meanwhile, 55 relays 3TFP and 3TBP follow the operation of track relay 3TR. In other words, during successive code pulses when front contact c of relay 3TR closes, relay 3TFP alternately operates to its reverse and normal positions. Relay 3TBP follows this operation during the corresponding off-period of the pulses, operating to its reverse 60 and normal positions immediately following the similar operation of relay 3TFP. With contacts b and c of relay 3TFP operating between their reverse and normal positions, relay 3RC is energized during each off-period of the master code by the discharge of capacitor C2, alternately operating its left (n) and right (r) contacts in the manner previously described. With front contacts an and bn of relay 3RC closed, a pulse of reverse code of positive polarity is transmitted through the rails of the 65 track section from battery 3TB. When front contacts

an and *br* of relay 3RC are closed during the succeeding off-period of the master code, a pulse of reverse code of negative polarity is transmitted through the rails of the track section. The positive and negative pulses of reverse code thus alternate during successive off-periods of the master code.

Track relay 2TR at the west end follows this reverse code, its left and right armatures being alternately responsive to alternately operate the corresponding sets of relay contacts. With front contacts *bn* and *br* of relay 2TR alternately closing to follow the reverse code, relays 2H and 2D, respectively, are periodically energized during the off-periods of the master code and pick up and hold. As previously mentioned, the capacitor-resistor snubs connected in multiple with each of the relay windings are engineered so as to hold the relay front contacts closed even when the relays are energized only during alternate pulses of the reverse code, regardless of the code rate of the master code being transmitted. Since signal 1G is displaying a clear indication, relay 1S is released and the circuit for energizing relay 2TP is periodically completed over back contacts *br* and *bn* of relay 2TR, in series, front contacts *a*, in multiple, of relays 2D and 2H, and back contact *a* of relay 1S. The half-wave rectifier snub is connected in multiple with the relay winding, as previously mentioned, over front contacts *a*, in multiple, of the other two decoding relays so that relay 2TP has sufficient slow release characteristics to hold its front contacts closed during this coding action. With the three decoding relays all energized and picked up, closing their front contacts, the circuit is completed for lamp G of signal 2G and this lamp is lighted to cause the signal to display the green aspect giving a clear indication.

I shall now assume that an eastbound train approaches section 2-3T. It is well known, as illustrated, for example, in the aforementioned Failor and Staples application, that the entry of the train into the single track stretch between stations causes the master code being received at signal location 1G to change to the 75 code rate. In fact, the master code throughout the stretch in any system embodying my invention will change to the 75 code rate. As illustrated by the decoding relays associated with signal 3G, only the code detecting relays CD will be energized upon the reception of master code of the 75 code rate so that signal 1G will provide a stop indication, that is, will display a red aspect. Relay 1GYP is thus deenergized and releases. Since relay 1S is also released, the circuit is completed to control relay 2CTP over contact *a* of code transmitter 75CT so that the master code transmitted from this location eastward through section 2-3T is also at the 75 code rate. At the east end, relay 3TR operates at the corresponding code rate, repeated by relays 180TP and 120TP. Contacts *a* of these latter relays are non-responsive to this rate, holding their back contacts closed so that relays 3D and 3H release and only relay 3CD remains energized at this time.

However, the reverse code transmitted from the location of signal 4G remains of alternate positive and negative pulses, although the rate of occurrence is slower, corresponding to the 75 code rate of the master code. This condition results because relay 4GYP remains energized, there being no change in the indication displayed by signal 4G. At the west end, track relay 2TR continues to operate its two sets of contacts alternately since the two armatures are alternately responsive to the reverse code pulses. Relays 2D, 2H, and 2TP remain periodically energized and hold their front contacts closed. Signal 2G thus continues to display a green aspect.

When the train enters section 2-3T, the rails are shunted and relay 2TR is deenergized so that all its contacts release. With contacts *bn* and *br* inoperative, relays 2H and 2D release at the end of their slow release

70 75

periods and interrupt the circuit for relay 2TP which shortly releases. The closing of back contact *b* of relay 2H initially energizes the red lamp of signal 2G and eventually back contact *a* of relay 2TP closes to energize the lamp. At the east end, relay 3TR is also shunted and, thus deenergized, releases. This halts the code following operation of relays 3TFP, 3TBP, and 3RC. Since relay 120TP is no longer periodically energized, its contact *b* remains released with the corresponding back contact closed so that relay 3CD is deenergized and shortly releases. By the time the train clears the section immediately adjacent the west end of section 2-3T, a directional stick relay similar to relay 4S at the east end is picked up to hold signal 1G at stop, the decoding relays for that section remaining deenergized.

As the train continues in the eastward direction and passes signal 4G, relay 4S is energized and picks up. When the train clears section 2-3T, that is, is entirely east of signal 4G, relay 3TR follows the master code at the 75 code rate being transmitted by relay 2CTP from the west end. Operation of relays 3TBP, 3TFP, and 3RC resumes at this time. However, with relay 4GYP released and relay 4S picked up, the contacts of relay 3TFP in the control circuits for relay 3RC are bypassed.

As previously described, the circuits established over front contacts *b* and *c* of relay 4S and back contacts *a* and *b* of relay 4GYP result in the flow of current pulses through the winding of relay 3RC, due to the periodic discharge of capacitor C2, being from left to right so that the normal armature only is responsive to operate the corresponding contacts. The periodic closing of front contacts *an* and *bn* of relay 3RC during each off-period of the master code cause the reverse code transmitted to have only the positive polarity.

Thus, at the west end, only the normal armature of relay 2TR is presently responsive to the reverse code pulses received and only its associated contacts operate to follow the code. The operation of contact *bn* of relay 2TR between its front and back positions energizes relays 2H and 2TP so that these relays pick up to close their front contacts. The circuit established over front contacts *a* and *b* of relays 2TP and 2H, respectively, and back contact *b* of relay 2D energizes the yellow lamp of signal 2G causing this signal to display an approach indication for a following train movement. At this time, the stick relay associated with signal 2G releases permitting the decoding circuits for the section to the west to function and resulting in the display of a clear indication by signal 1G. This operation energizes relay 1GYP which picks up, closing its front contact *a* to complete the circuit for controlling relay 2CTP over front and back contact *a* of transmitter 180CT. The master code pulses being transmitted eastward are thus restored to the 180 code rate. However, since relay 4S at the east end of the section is energized, its open back contact *a* interrupts the circuits for all the decoding relays and relays 3D, 3H, and 3CD remain deenergized so that signal 3G continues to display a red aspect. It is obvious that, as the train continues eastward eventually clearing the section adjacent the east end of section 2-3T, relay 4S will release when signal 4G displays an approach indication. The closing of back contact *a* of relay 4S reenergizes the decoding relays to permit the display of a proceed indication by signal 3G. Relay 4GYP is energized and picks up at this time, resulting in the restoration of the alternate positive and negative pulses of reverse code. The system shown for section 2-3T is at this time restored to its normal condition as shown in the drawings.

It is now assumed that a westbound train approaches section 2-3T. In a manner similar to that to be described shortly for signal 2G, the A.P.B. signaling system operates to place signal 4G at its stop indication, that is, displaying a red aspect. Relay 4GYP is thus deenergized and releases. Since relay 4S is likewise released,

the circuit for controlling relay 3RC is established over back contacts *a* and *b* of relay 4GYP and back contacts *b* and *c* of relay 4S. This bypasses contacts *b* and *c* of relay 3TFP and results in a flow of current through the relay winding from right to left so that only the right armature of relay 3RC is responsive, operating the associated contacts in accordance with the code following operation of relay 3TR in the manner previously described. The periodic closing of front contacts *ar* and *br* of relay 3RC results in the transmission, through the rails of section 2-3T to the west end, of reverse code pulses having only a negative polarity.

At the west end, the flow of track current through relay 2TR is from right to left, as will be obvious with negative polarity pulses, so that only the right armature of relay 2TR is responsive to the reverse code pulses, operating the associated contacts periodically. Front contact *br* of relay 2TR is periodically closed while contact *bn* remains in its released position closing the corresponding back contact. Under these conditions, relays 2D and 2TP remain energized and relay 2H is deenergized and releases at the end of its slow release period. The closing of back contact *b* of relay 2H establishes a circuit for energizing lamp R of signal 2G and the signal thus displays its red aspect. From the previous description, it will be obvious that the corresponding action cascades through the section immediately to the west of signal 2G. If signal 1G is approach lighted, the continued energization of relay 2TP at this time will retain the signal lamps dark so that the approach lighting is effective section by section and not throughout the whole stretch of single track between the stations. If there is no change in the clear indication displayed by signal 1G, relay 1GYP remains energized and relay 2CTP continues to be controlled by front and back contacts *a* of transmitter 180CT. The master code transmitted eastward through section 2-3T thus remains at the 180 code rate so that signal 3G remains in its clear position.

When the westbound train enters section 2-3T, the track circuits are shunted and relays 2TR and 3TR release. At the east end, relays 180TP and 120TP are deenergized at this time, their circuits being open at front contacts *a* and *b* of track relay 3TR. With relays 180TP and 120TP released so that their back contacts remain continuously closed, decoding relays 3D, 3H, and 3CD are deenergized and release at the end of their slow release periods. The release of relay 3H energizes the red lamp of signal 3G and the signal displays a stop indication. At the west end, the non-operation of contact *br* of relay 2TR deenergizes relay 2D and when this relay releases to open its front contact *a*, relay 2TP is likewise deenergized and quickly releases, its snubbing circuit being open at this time also. The release of relay 2TP causes the selected lamp of signal 1G to be lighted in preparation for the approach of the westbound train. When the train clears the section immediately to the east of signal 4G, coding action may resume in that section, but the directional stick relay associated with signal 3G, which corresponds in operation to relay 1S at the west end of the section shown, prevents energization of the track repeater relay so that the signal 4G remains with the red lamp energized.

When the westbound train passes signal 1G, the signal is operated to its stop position in a manner similar to that previously described for signal 3G. Relay 1S is also energized at this time and picks up. Thus, when the train clears section 2-3T, relay 2CTP is controlled by contact *a* of transmitter 120 CT, the circuit including back contact *a* of relay 1GYP and front contact *b* of relay 1S. The master code transmitted eastward through section 2-3T is thus of the 120 code rate and track relay 3TR operates at a corresponding frequency. Relays 180TP and 120TP are also energized by code pulses at the 120 code rate so that front contact *a* of relay 120TP is periodically closed since it is tuned to be responsive

to this code rate. Contact *a* of relay 180TP remains closed in its back position. At this time then, relays 3H and 3CD are energized. The closing of front contact *a* of relay 3H completes a circuit over back contact *a* of relay 3D for energizing lamp Y of signal 3G causing that signal to display a yellow aspect providing an approach indication for a following train.

The release of directional stick relay associated with signal 3G permits signal 4G to operate to its clear position so that relay 4GYP is energized and picks up. The closing of front contacts *a* and *b* of relay 4GYP returns the control of relay 3RC to contacts *b* and *c* of relay 3TFP. This latter relay, of course, is alternately operating between its normal and reverse positions following the operation of relay 3TR at the 120 code rate. The two armatures of relay 3RC are alternately responsive to the current flowing through the relay winding and the alternate operation of contact pairs *an*-*bn* and *ar*-*br* of relay 3RC transmits reverse code pulses of alternate positive and negative polarities. Relay 2TR follows this combination code, alternately operating its normal and reverse armatures and contacts. The alternate closing of front contacts *br* and *bn* of relay 2TR energizes relays 2D and 2H. However, although front contacts *a* of relays 2D and 2H are closed, the open back contact *a* of relay 1S prevents the energization of relay 2TP and this latter relay remains released. The red lamp of signal 2G continues to be energized over back contact *a* of relay 2TP and the signal continues to display its stop indication.

When the westbound train clears the section immediately adjacent the west end of section 2-3T, signal 1G is controlled to display its approach indication in a manner similar to that previously described for signal 3G. Relay 1GYP picks up and changes the operation of relay 2CTP to the 180 code rate, the master code thus returning to this rate immediately. In a manner previously described, the decoding arrangement at the east end of the section operates to cause signal 3G to display a clear indication. Relay 1S releases at this time, permitting the energization of relay 2TP which picks up. With contacts *b* of relays 2H and 2D already closed, the closing of front contact *a* of relay 2TP completes the circuit for energizing lamp G of signal 2G and this signal returns to its clear position displaying a green aspect. The signal system for section 2-3T is thus restored to the condition shown in the drawings.

It is obvious from the above description of the operation of the system for train movements in each direction that, if following moves do occur, similar action will take place for each train movement through section 2-3T. Reference is also made to the aforementioned Failor and Staples application for a more detailed description of such following moves and the complete operation of the A.P.B. signaling system. It is believed to be unnecessary herein to completely describe in detail the action occurring as following moves take place.

Referring now to Fig. 2, I shall describe a second form of reverse code generator and associated apparatus which also embodies my invention. In Fig. 2, only the apparatus at the east end of section 2-3T is shown. However, this apparatus cooperates with the apparatus shown at the west end of the section in Fig. 1. No change in the arrangement at this latter end of the track section is necessary for proper operation of the second form of the reverse code generator. The reverse code generator shown in Fig. 2 is of the general type shown in the aforementioned Failor and Staples application, that is, the three relay, fast application method. As herein shown, it is modified and improved to embody the teachings of my invention to provide three combinations of reverse code pulses to carry active information through the track section. This second form of invention also utilizes some of the additional advantages available due to the physical features of the code following relay with

the mechanically tuned decoding contacts disclosed in the aforementioned Hufnagel patent.

Track relay 3TRA shown in the upper right of Fig. 2 is, in this form of the circuit arrangement, a relay such as disclosed in the Hufnagel patent. There is also provided a code following front contact repeater of the track relay, relay 3TP, which repeats directly the coding action of track relay 3TRA. Relay 3TP is also of the type having a mechanically tuned contact disclosed in the previously mentioned patent. Two reverse code transmitter relays are provided to transmit respectively the positive and negative code pulses. Positive reverse code transmitter relay PRC and negative reverse code transmitter relay NRC are selected, as will be described shortly, over contacts of a pole changing relay PC which is of the magnetic stick type previously described. However, in this form of the circuit arrangement, this magnetic stick relay has only a single winding. In the decoding arrangement for the master code at this location, the previously described distant relay 3D, home relay 3H, and code detecting relay 3CD are again utilized. In addition, there is provided a slow release front contact repeater of track relay 3TRA, the relay 3TFPA. As will be described shortly, this latter relay, in combination with relay 3CD, provides a code detecting arrangement to check the code following action, that is, the alternate closing of front and back contacts, of both the track relay 3TRA and the track repeater relay 3TP.

Track relay 3TRA follows the master code pulses received over the track rails from the west end of the section as transmitted by relay 2CTP. At the beginning of each master code pulse, relay 3TRA is initially energized through a circuit from one rail of the section over track lead (+), the winding of relay 3TRA in the direction of the arrow, back contact *a* of relay PRC, back contact *b* of relay NRC, and track lead (-) to the other rail of the section. The back contacts of the two reverse code transmitter relays in this circuit assure that the master code pulse is effective only if no reverse code pulse is being transmitted and the reverse code relays are not inadvertently held energized due to some circuit fault. Track relay 3TRA is held energized by a stick circuit including the two track leads, the relay winding, and its own front contact *a*. This circuit is effective to hold relay 3TRA energized until the master code pulse itself terminates, the interruption of the initial circuit by the opening of the back contact of either reverse code transmitter relay having no effect under this condition.

The closing of front contact *b* of relay 3TRA completes an obvious circuit for energizing relay 3TP, this circuit being effective to periodically energize relay 3TP to also follow the master code pulses received. Each of these relays is provided, as previously mentioned, with a mechanically tuned contact *c*. Contact *c* of relay 3TRA is tuned at the 180 code rate so that it follows, alternately closing front and back contacts, only when master code pulses are of this code rate. Contact *c* of relay 3TP is tuned at the 120 code rate and it follows the operation of relay 3TP only when the master code pulses are of the 120 code rate. Each of these contacts is designated by the conventional symbol, a line drawn through the heel of the movable portion of the contact. As previously described, these contacts remain released, closing the corresponding back contact, except when the relay is energized at the code rate to which the contact is tuned. The other two contacts of each relay alternately close the corresponding front and back contacts when the relay is energized at any code rate.

The decoding circuit arrangement herein provided functions, as will be described, in the manner similar to that for the coding arrangement described in connection with Fig. 1 and provides the same results in keeping with the master code rate received. Relay 3TFPA is energized by a circuit extending from terminal B over back contact *a* of directional stick relay 4S, front contact *a* of relay

3TP, and the winding of relay 3TFPA to terminal N. It is obvious that, with back contact *a* of relay 4S closed, relay 3TFPA is periodically energized when relay 3TP is following code pulses of any code rate. Relay 3TFPA is snubbed by a half-wave rectifier connected in multiple with the relay winding and is sufficiently slow release with this arrangement to bridge the open circuit time of front contact *a* of relay 3TP. Relay 4S is identical with relay 4S shown in Fig. 1 and its operation has previously been sufficiently described. Back contact *a* of this latter relay interrupts the supply of energy from terminal B to the decoding arrangement and thus assures that signal 30 will display a red aspect, that is, a stop indication, behind any eastbound train moving through the track section immediately east of section 2-3T. This function is the same as previously described in connection with the arrangement in Fig. 1.

Code detecting relays 3CD checks the proper code following operation of contact *a* of relay 3TP and also the proper operation of contacts *c* of this relay and relay 3TRA. The circuit for energizing relay 3CD extends from terminal B over back contacts *a* of relays 4S and 3TP, front contact *a* of relay 3TFPA, the winding of relay 3CD, and back contacts *c*, in series, of relays 3TP and 3TRA to terminal N. Relay 3CD is provided with a snubbing circuit including a resistor-capacitor arrangement which is connected in multiple with the relay winding over front contacts *b* and *a* of relay 3TFPA. Relay 3CD has slow release characteristics only when this capacitor-resistor snub is connected in multiple with the relay winding. The relay itself is provided with slow pick-up characteristics, these slow acting characteristics being indicated by a double arrow through each of the relay contacts. The snubbing arrangement is shunted, when relay 3TFPA is released, over back contact *b* of this relay. This shunt assures that the capacitor is discharged during such periods and assists the proper functioning of the slow pick-up characteristics of relay 3CD. The combination of relays 3TFPA and 3CD assures correct code following operation of all relay contacts involved in the decoding arrangement, that is, contact *c* of relay 3TRA and contacts *a* and *c* of relay 3TP. It will be obvious from the remaining decoding circuits described shortly that, unless relays 3TFPA and 3CD are both energized and picked up, the proper decoding of the received master code pulses cannot be accomplished.

When master code of the 180 code rate is received so that the operation of relay 3TRA is at the same code rate, distant relay 3D is energized by the circuit extending from terminal B through the relay winding, front contact *b* of relay 3CD, and front contact *c* of relay 3TRA to terminal N. This latter contact is periodically closed under these conditions since it is tuned at the 180 code rate and relay 3D is periodically energized and picks up. This relay is held up by the half-wave rectifier snub connected in multiple with the relay winding over front contact *b* of relay 3CD. If the master code pulses are of the 120 code rate, relay 3H is energized rather than relay 3D, the circuit for relay 3H including the relay winding, front contact *a* of relay 3CD, front contact *c* of relay 3TP, and back contact *c* of relay 3TRA. Relay 3H is periodically energized by the code following operation of contact *c* of relay 3TP under these conditions since this contact is tuned at the 120 code rate. Relay 3H picks up and is held in this position by the half-wave rectifier snub connected in multiple with the relay winding over front contact *a* of relay 3CD. Each of these latter two decoding relays releases quickly after the release of relay 3CD when the code reception halts, the snub for each relay being interrupted by the opening of front contacts of relay 3CD. When color light signals are used, the circuit arrangement for controlling the operation of signal 3G is the same as that shown in Fig. 1 and it is believed unnecessary to again show or describe these circuits in connection with the second form of my invention. Of course,

it is to be understood that any other type of signal may be used and the circuit arrangement controlling the signal varied in accordance with the type of signal used.

The reverse code transmitter relays are, in effect, front contact repeaters of track repeater relay 3TP. Each of the reverse code transmitter relays is snubbed by a resistor connected in multiple with the relay winding, although the retardation is not such as to class the relays as slow release. The snub is used only to improve the form and length of the reverse code pulses, that is, the on-period of the reverse code, in order to provide better operation of the system. The circuit for negative reverse code transmitter relay NRC extends from terminal B over front contact *b* of relay 3TP, reverse contact *a* of relay PC, and the winding of relay NRC to terminal N. The circuit for the positive reverse code transmitter relay PRC also includes front contact *b* of relay 3TP and then extends over normal contact *a* of relay PC, front contact *a* of relay 4GYP in multiple with front contact *b* of relay 4S to the winding of relay PRC. Relay 4GYP, as previously mentioned as for relay 4S, is identical with the similarly designated relay shown in Fig. 1. The operation of relay 4GYP has thus been previously described and is not believed necessary to repeat the description here.

It is obvious from the circuits just described that the reverse code transmitter relays are selected over normal and reverse contacts of pole changing relay PC. This latter relay is energized periodically over back contact *b* of relay 3TP so that its energization occurs during the off-period of the master code and thus alternately with the energization of one of the reverse code transmitter relays. During normal operation of this system, that is, when no train occupies the section or is approaching from either direction, relay PC is energized over a first circuit which is traced from terminal B over back contact *b* of relay 3TP, front contact *b* of relay 4GYP, front contact *c* of relay PRC, normal contact *b* and the winding of relay PC, back contact *c* of relay NRC, and back contact *c* of relay 4S to terminal N. It is obvious that this circuit is complete at the beginning of an off-period of the master code following an on-period when relay PRC has been energized, the release of relay PRC, as previously mentioned, being slightly retarded beyond the termination of the pulse of master code. The flow of current through the winding of relay PC in the circuit just described is such as to cause the relay to operate its contacts to the reverse position, closing reverse contact *b* of the relay. This prepares a second circuit for energizing relay PC which includes back contact *b* of relay 3TP, front contact *b* of relay 4GYP, front contact *c* of relay NRC, and the winding and reverse contact *b* of relay PC. The flow of current in this circuit from terminal B to terminal N through the relay winding is in the direction of the arrow and relay PC operates its contacts to their normal position. This second circuit exists at the beginning of an off-period of the master code following an on-period when relay NRC was energized and picked up. Since both circuits include front contact *b* of relay 4GYP, signal 4G must be in its clear position for this alternate operation to occur.

The operation of relay PC thus occurs alternately between its reverse and normal positions and relays PRC and NRC are alternately selected for energization when front contact *b* of relay 3TP closes. As will be shortly described, the alternate energization of these two reverse code transmitter relays on successive pulses of master code results in the transmission of alternate positive and negative reverse code pulses through the track section.

If signal 4G displays a red aspect and relay 4S is energized, a circuit for relay PC may extend from terminal B over back contact *b* of relay 3TP, back contact *b* of relay 4GYP, front contact *d* of relay 4S, back contact *c* of relay NRC, and the winding and reverse contact *b* of relay PC to terminal N. This circuit exists as an east-bound train passes signal 4G, after relay 4S picks up,

unless relay PC already occupies its normal position, which it then holds. The flow of current in the last traced circuit through the winding of relay PC is in the direction of the arrow and relay PC operates to its normal position. It is obvious that during the following on-period of the master code, relay PRC is energized over normal contact *a* of relay PC and front contact *b* of relay 4S. However, when relay 3TP again releases during the next master code off-period to close its back contact *b*, the circuit for relay PC over its normal contact *b* is open at front contact *b* of relay 4GYP while front contact *c* of relay PRC is closed and at back contact *d* of relay 4S when back contact *c* of relay PRC closes. Since relay PC remains in its normal position, the periodic closing of front contact *b* of relay 3TP continues to periodically energize relay PRC only. As will be shortly described, the sole operation of relay PRC causes the transmission of only positive reverse code pulses through the track section.

If relays 4S and 4GYP are both released, as is the condition when a westbound train is approaching the circuit for relay PC includes back contact *b* of relay 3TP, back contact *b* of relay 4GYP, back contact *d* of relay 4S, back contact *c* of relay PRC, normal contact *b* and the winding of relay PC, and back contacts *c*, in series, of relays NRC and 4S. The flow of current between terminals B and N through this circuit is in the direction opposite to the arrow in the winding of relay PC and this relay operates to its reverse position. During the next on-time of the master code, relay NRC is energized over reverse contact *a* of relay PC, as previously described. During the next off-period of the master code, the circuit including reverse contact *b* of relay PC and front contact *c* of relay NRC is open at front contact *b* of relay 4GYP. When relay NRC releases, a shunt is placed on the winding of relay PC traced from terminal N over reverse contact *b* and the winding of relay PC, back contact *c* of relay NRC, and back contact *c* of relay 4S to terminal N. Relay PC thus remains in its reverse position and relay NRC alone is periodically energized during each on-time of the master code. This results, as will be described shortly, in the transmission of only negative pulses of reverse code.

The periodic operation of relays PRC and NRC, either in combination or singly, results in the transmission of reverse code pulses through the rails of the section. One circuit may be traced from the positive terminal of track battery 3TB over front contact *a* of relay PRC, the winding of relay 3TRA in the direction opposite to the arrow, and track lead (+) to one rail of the section returning from the other rail over track lead (-), back contact *a* of relay 3TRA, and front contact *b* of relay PRC to the negative terminal of track battery 3TB. Thus, when relay PRC is energized and picks up to close its front contacts, a positive polarity pulse of reverse code is transmitted. A second circuit is traced from the positive terminal of track battery 3TB over front contact *a* of relay NRC, back contact *a* of relay 3TRA, and track lead (-) to one track rail and returning from the other track rail over track lead (+) and back contact *b* of relay PRC to the negative terminal of the track battery. The circuit through the winding of relay 3TRA under these conditions is open at back contact *b* of relay NRC. Thus, when relay NRC is energized and picks up to close its front contacts, a negative polarity pulse of reverse code is transmitted. It is thus obvious that the sole operation of relay PRC or relay NRC results in the transmission of positive or negative reverse code pulses, respectively. However, the alternate operation of the two reverse code transmitter relays results in the transmission of alternate positive and negative reverse code pulses during the off-times of the master code.

Referring to Fig. 1 briefly, the decoding circuits for reverse code at the west end of the track section, which were previously described, result in the energization of

both relays 2D and 2H if positive and negative pulses are alternately transmitted. Positive polarity reverse code pulses only result in energization of only relay 2H, while negative reverse code pulses only result in the energization of only relay 2D. This operation was previously described and needs only to be mentioned here. With both decoding relays up, as well as the code detecting relay 2TP which picks up with either or both code pulses, the combination of positive and negative pulses results in a green aspect on signal 2G. With positive polarity pulses only and relays 2H and 2TP picked up, the yellow aspect is displayed by signal 2G resulting in an approach indication. Negative reverse code pulses only, which result in relays 2D and 2TP being energized, cause the display of the red aspect by signal 2G, this reverse code combination being used for other purposes previously described.

The operation of the signal system for section 2X3T, using the second form of my invention, during the passage of trains in each direction, is very similar to that described in connection with the arrangement of Fig. 1. Accordingly, it is believed that the operation can be fully understood by reference to this preceding description and that it is not necessary to again describe the operation.

It is thus evident that the reverse code generator provided by my invention permits three combinations of reverse code pulses to be transmitted through the rails of the section, thus carrying three active indications in addition to the no-code indication. This system makes possible a simpler system arrangement for A.P.B. signaling. In part, this is due to the ability to obtain overlap control from the reverse code as well as from the master code and eliminates the necessity for reversing the direction of flow of the two track codes from one section to another. In addition, approach lighting of signals controlled by the master code may be effected section by section through the use of the additional indications supplied by the reverse code pulses. With the positive and negative reverse code pulses in combination occurring alternately during successive off-times of the master code, sufficient reverse code on-time is available to operate the decoding relays as shown in Fig. 1, it being noted that it is well known to provide sufficient snub to hold the relays picked up even if energized only every alternate pulse of code. Thus the system of my invention results in the ability to supply three active indications in the reverse code direction, similar to the three active indications supplied in the master code direction in the usual coded track system.

Although I have herein shown and described but two forms of apparatus embodying the reverse code generator of my invention, it is to be understood that various changes and modifications may be made therein within the scope of the appended claims without departing from the spirit and scope of my invention.

Having thus described my invention, what I claim is:

1. A coded track signaling system for a section of track, comprising, means for supplying spaced pulses of master code to the section, reverse code means for supplying reverse code pulses to said section and controlled by each master code pulse for initiating the transmission of a single reverse code pulse of only a single polarity between any two master pulses, and traffic responsive means for controlling the polarity of said reverse code pulses in response to traffic conditions to cause the transmission at times of reverse pulses all of a first polarity, at times the transmission of reverse pulses all of a second polarity, and at still other times the transmission of reverse pulses alternately of said first and said second polarity.

2. A coded track signaling system for a section of track, comprising, means for supplying to the section spaced pulses of master code, code responsive means operatively connected to said section and controlled by said pulses from a first to a second condition, traffic re-

sponsive means operable to a first, second, and a third condition, means controlled by said code responsive means in its second condition and said traffic responsive means in its first condition for applying reverse code pulses of a first polarity to said section between said master code pulses, means controlled by said code responsive means in its second condition and said traffic responsive means in its second condition for applying reverse code pulses of a second polarity to said section between said master code pulses, and means controlled by said code responsive means in its second condition and said traffic responsive means in its third condition for applying reverse code pulses of alternate first and second polarity, one reverse code pulse of a single polarity being applied to said section between each pair of successive master code pulses.

3. In a coded track signal system for a section of railway track including a master code generator connected to said section for supplying spaced pulses of master code to said section at one end thereof, a reverse code generator connected to said section at the opposite end thereof and effective to transmit reverse code pulses of a first polarity, a second polarity, or alternately of said first and said second polarity in accordance with advance traffic conditions beyond said section in the traffic direction governed by said reverse code, and means for shifting to a first, second and third condition in response to first, second and third advance traffic conditions, respectively, beyond said section in the traffic direction governed by said reverse code, said reverse code generator comprising, in combination, a track relay connected to said section and responsive to master code pulses, a transmitter relay means having first and second position contacts, a control circuit means controlled by code following contacts of said track relay and said advance traffic responsive means for controlling said transmitter relay means to periodically close its first position contacts when said first advance traffic condition exists, to periodically close its second position contacts when said second advance traffic condition exists, and to alternately close first and second position contacts when said third advance traffic condition exists, and a track circuit means having connections to said section and controlled by first and second position contacts of said transmitter relay means for transmitting through said section reverse code pulses of a first polarity when said first position contacts are closed and of a second polarity when said second position contacts are closed.

4. In a coded track signaling system for a track section, means for supplying spaced master code pulses to said section, means responsive to said master code pulses for at times transmitting reverse code pulses of a selected polarity through said section, one pulse of only one polarity between each successive pair of master code pulses, and means controlled by traffic conditions beyond said section in the direction controlled by said reverse code pulses for selecting a first polarity, a second polarity, or said first and said second polarity alternately for said reverse code pulses as the traffic beyond is of a first, a second, and a third condition respectively.

5. A coded track signal system for a section of single track having an entering signal at each end to govern traffic in opposite directions entering said section, comprising, a master code transmitting means having connections to the rails at a first end of said section for selectively transmitting one of a plurality of code rates, a master code decoding means having connections to the rails at a second end of said section and responsive to said master code pulses for operating the second end entering signal in accordance with the received code rate; a traffic responsive means operable to a first, a second, and a third condition in accordance with traffic conditions in the section adjacent said second end; a feedback code transmitting means at said second end controlled in response to the reception of master code pulses

and having connections to the rails for transmitting feedback pulses during the intervals between said master code pulses, one feedback pulse of only one polarity for each master code pulse; said feedback transmitting means being further controlled by said traffic responsive means for establishing the polarity of said feedback pulses to be a first polarity, a second polarity, or alternately said first and said second polarity as said traffic responsive means is in its first, second, and third conditions respectively; and feedback decoding means at said first end having connections to the rails and controlled in response to said feedback pulses for operating the first end entering signal in accordance with the polarity of the received feedback pulses.

6. A coded track signal system for a section of single track having an entering signal at each end to govern traffic in opposite directions entering said section, comprising, a master code transmitting means having connections to the rails at a first end of said section for selectively transmitting through the section rails one of a plurality of code rates, a master code decoding means having connections to the rails at a second end of said stretch and responsive to the reception of said master code pulses for operating the second end entering signal in accordance with the master code rate; a traffic responsive means operable to a first, a second, and a third condition; a transmitter relay means controlled in response to the reception of master code pulses at said second end and by said traffic responsive means for periodically closing, once in response to each master code pulse, a first set of contacts, a second set of contacts, or said first and said second set alternately according as said traffic responsive means is in its first condition, its second condition, or its third condition respectively; and a reverse coding means controlled by said first and said second contacts of said transmitter relay means and having connections to the rails at said second end for transmitting feedback pulses through the rails of a first polarity and a second polarity according as said first and said second contacts are closed; and feedback decoding means having connections to the rails at said first end and responsive to the reception of said feedback pulses for operating the first end entering signal in accordance with the polarity of the feedback pulses.

7. A coded track signaling system for a section of track, comprising, means for supplying to the section spaced pulses of master code, a track relay connected to the section and responsive to said master code pulses to operate alternately to a first and a second position, a front contact repeater relay having a first and a second winding and a first and a second set of contacts respectively closed in response to the energization of said first and said second windings, a back contact repeater relay having a first and a second winding and a first and a second set of contacts respectively closed in response to the energization of said first and said second windings, circuit means controlled by a first position contact of said track relay and by a first and a second contact of said back repeater relay for energizing said second and said first windings respectively of said front repeater relay, another circuit means controlled by a second position contact of said track relay and by a first and a second contact of said front repeater relay for energizing said first and said second windings respectively of said back repeater relay; a traffic responsive means having a first, a second, and a third condition; a reverse code relay operable to a first, a second, and a third position, means controlled by first position contacts of said reverse code relay for supplying to the section a reverse code pulse of a first polarity, means controlled by second position contacts of said reverse code relay for supplying to said section a reverse

code pulse of a second polarity, a first energizing circuit for said reverse code relay including a source of energy, a second position contact of said track relay and first condition contacts of said traffic responsive means to periodically operate said reverse code relay to its first position, a second energizing circuit for said reverse code relay including a source of energy, a second position contact of said track relay and second condition contacts of said traffic responsive means to periodically operate said reverse code relay to its second position; and a third energizing circuit for said reverse code relay including a source of energy, a second position contact of said track relay, third condition contacts of said traffic responsive means, and first and second contacts of said front repeater relay to periodically operate said reverse code relay alternately to its first and second positions.

8. A coded track signaling system for a section of track, comprising, means for supplying to the section spaced pulses of master code, a track relay connected to the section and responsive to said master code pulses to operate alternately to a first and a second position, a first reverse code relay operable to a first position and normally occupying a second position, a second reverse code relay operable to a first position and normally occupying a second position, a first coding circuit means controlled by first position contacts of said first reverse code relay and a second position contact of said track relay for supplying to said section a reverse code pulse of a first polarity, a second coding circuit means controlled by a first position contact of said second reverse code relay and second position contacts of said track relay and said first reverse code relay for supplying to said section a reverse code pulse of a second polarity, a pole-changing relay operable to a first and a second position; traffic responsive means having a first, a second, and a third condition; a first circuit means controlled by said traffic responsive means in its first condition, by a contact closed when said track relay is in its second position, and by second position contacts of both reverse code relays for operating and holding said pole-changing relay in its first position; a second circuit means controlled by said traffic responsive means in its second condition, by a contact closed when said track relay occupies its second position, and by second position contacts of both reverse code relays for operating and holding said pole-changing relay to its second position; a third circuit means controlled by said traffic responsive means in its third condition, by a contact closed when said track relay occupies its second position, and by first and second position contacts of both reverse code relays for alternately operating said pole-changing relay to its first and its second position following successive master code pulses, an energizing circuit for said first reverse code relay including a contact closed when said track relay occupies its first position, a first position contact of said pole-changing relay, and contacts in multiple closed when said traffic responsive means is in its first and third conditions to at times periodically operate said first reverse code relay to its first position, and an energizing circuit for said second reverse code relay including a contact closed when said track relay occupies its first position and a second position contact of said pole-changing relay to at times periodically operate said second reverse code relay to its first position.
